UNITED STATES PATENT OFFICE.

CHARLES F. STACKPOLE, OF LYNN, MASSACHUSETTS, ASSIGNEE, BY MESNE ASSIGNMENTS, TO THE TURNER TANNING MACHINERY COMPANY, OF BOSTON, MASSACHUSETTS, A CORPORATION OF MAINE.

SCARFING-MACHINE.

No. 857,682.

Specification of Letters Patent,

Patented June 25, 1907.

Application filed February 15, 1904. Serial No. 193,532.

To all whom it may concern:

Be it known that I, CHARLES F. STACKPOLE, a citizen of the United States, residing in Lynn, in the county of Essex and State of Massachusetts, have invented an Improvement in Scarfing-Machines, of which the following description, in connection with the accompanying drawings, is a specification, like letters on the drawings representing like parts.

This invention relates to a machine for scarfing leather or like material, and has for its object to provide a machine with which pieces of leather of different thickness, and particularly pieces of belt leather, may be cut so as to leave scarfs or bevels of substantially uniform length and of the same angle of inclination, and whereby the cut may be made so as to leave a thin edge, without tearing the leather, with the least possible amount of scarfing by hand, and without waste of material.

The invention is particularly applicable to a machine employing an endless band or belt knife and provision is made for attaching the invention to and detaching it from said machine so that the machine without the invention applied thereto may be used as a splitting machine in the usual manner, and with the attachment thereon may be used for scarfing purposes.

In accordance with this invention, provision is made for automatically controlling the movement of the gage roll toward the plane in which the knife travels, so that the different pieces of leather may be cut on the same angle and the cut may be made of substantially the same length, irrespective of variations, within limits, in the thickness of the pieces of leather acted upon. Provision is also made for varying the angle and the length of the cut as desired. For this purpose, I employ a gage which is movable with relation to the gage roll, and make provision for automatically stopping the said gage when it reaches the limit of its travel in opposite directions. These and other features of this invention will be pointed out in the claim at the end of this specification.

Figure 1 is a front elevation of a belt knife splitting machine embodying this invention. Fig. 2, an end elevation of the machine shown in Fig. 1, looking toward the left.

Fig. 3, a detail in side elevation and on an enlarged scale to be referred to. Fig. 4, a partial plan and section of the parts shown in Fig. 3. Fig. 5, a vertical section on the line 5—5, Figs. 3 and 4. Fig. 6, a sectional detail on an enlarged scale on the line 6—6, Fig. 1, showing the gage roll in what may be termed its starting position. Fig. 7, a sectional view like Fig. 6 showing the gage roll in the position it occupies when the scarf is partially cut. Fig. 8, a sectional detail on an enlarged scale, taken on the line 8—8, Figs. 3 and 4. Fig. 9, a detail in elevation and on an enlarged scale to be referred to, and Fig. 10, a cross section on a reduced scale taken on the line 10—10, Fig. 3.

In the present instance, I have shown the invention as applied to a belt knife splitting machine, which consists essentially of a bed roll *a* provided with a rubber covering *b*, the sectional ring roll *c* co-operating therewith, the gage roll *d*, the endless band or belt knife *f*, the wheels or pulleys *h*, *i*, supported at opposite ends of the frame *j*, and over which the said knife is passed, the guiding plates or jaws *k* between which the knife is passed and supported in close proximity to the ring roll *c*, the tables *l*, *m* co-operating with the ring roll, the shaft *n* provided with the belt pulley *o* and bevel pinion *q* in mesh with the bevel gear *r* on the shaft *s* of the pulley *h*, and the gearing *t* for rotating the bed roll and gage roll are and may be of any usual or suitable construction. The gage roll *d* is movable toward and from the ring roll and is supported in bearings 12 (see Fig. 5), which are secured to a movable head or carrier, comprising metal side pieces 13, 14 separated at their lower edges to leave an opening through which the gage roll may project as represented in Figs. 6 and 7. The side pieces 13, 14 are secured to or form part of end pieces 15, 16 connected by a web or cross piece 16, and said side pieces are provided with guiding ribs 17 (see Fig. 4) which extend into guideways 18 in the sides 19 of the framework of the machine. The end pieces 15 of the gage roll carrier are provided with substantially horizontal arms 20, which project beyond the sides of the frame of the machine and between which arms and lugs 21 on said frame, are interposed helical springs 22, which act to lift the gage roll carrier, which may be

lowered in opposition to said springs by means of a handle or lever 23 fast on a rock-shaft 24 supported in bearings in the sides of the framework, the said rock-shaft having 5 cranks or arms 25, which are connected by links 26 with bolts 27 fastened to the arms 20 of the said carrier.

The gage roll *d* may be held from springing under pressure by re-enforcing or backing 10 rolls 28 (see Fig. 6), supported above and in contact with the gage roll by means of rods 29 screw-threaded at their upper end to be engaged by nuts 30, 31, which are interposed between the web or cross bar 16 and guide 15 blocks or pieces 32, which are fitted between the sides 13, 14 of the gage roll carrier, and centered or accurately adjusted by means of threaded plugs or centering pieces 33, which are extended through threaded holes in the 20 sides of the said carrier and accessible from the outside of the machine, as represented in Fig. 1.

The machine as thus far described is adapted to be used for splitting leather after the 25 manner of an ordinary belt knife leather splitting machine.

The primary object of the present invention, is to provide the leather splitting machine with mechanism, which may and preferably will be in the form of an attachment, 30 by means of which leather and other material and particularly leather belting, may be scarfed or beveled at its ends, in such manner as to enable the leather to be cut to a very thin edge without liability of tearing the leather, without waste of material, and so 35 that the bevels are of substantially uniform length irrespective of the thickness within limits of the leather, thereby enabling leather 40 to be uniformly scarfed at a minimum cost. To this end, the machine is provided with a gage or device for controlling the movement of the gage roll toward the ring roll, whereby 45 the leather is presented to the action of the knife in such manner, that the said knife effects a cut of substantially uniform length on an incline or angle predetermined by the gage or controlling device and irrespective of the thickness, within limits, of the leather.

50 The gage or controlling device is preferably adjustable, whereby it can be moved into any desired position at an angle to the plane in which the leather is moved, so that the leather may be cut on any desired angle and 55 the scarf made of any desired length within limits.

Provision is made for moving the gage or controlling device simultaneously with the leather as the latter is fed out of the machine, 60 and provision is also made for automatically returning the gage to its starting position.

In the present instance, I have shown one form of gage or controlling device, which may be made as herein shown (see Fig. 3) and 65 consists of a lever or arm 40 secured to a car-

rier, herein shown as a rack bar 41 movable in a substantially horizontal guide-way in a frame or support 42 (see Fig. 10), which is attached to the side frame of the machine as by bolts 43, the said rack bar being retained in 70 its guide way by strips or pieces 44, 45, secured to the support or frame 42 by screws 46, 47, so as to leave the side of the rack bar exposed as shown in Fig. 3.

The rack bar 41 is provided on its front or 75 exposed side with a T-shaped slot 48 (see Fig. 10) extended longitudinally of the said bar, and within the enlarged portion of which is fitted the head of a bolt 49, which is extended through one end of the lever or bar 80 40 and through a cam plate 50, the said bolt being provided with a nut 51 by which the cam plate 50 and the gage 40 may be firmly clamped to the rack bar 41 to move therewith. The cam plate 50 may be provided 85 with a guide pin 510 which is extended into the slot 48 in the rack bar.

The gage 40 may be provided on its inner side with a longitudinally extended slot or groove 52 (see dotted lines, Fig. 3), into 90 which extends a stud or projection 54 on the end of a spring rod or bar 55 attached to the side of the rack bar 41 and as shown in Fig. 3 set into a recess 56 in said rack bar.

The rack bar and its attached gage are and 95 may be moved in a plane substantially at right angles to the plane in which the gage roll *d* is moved bodily, by mechanism as will now be described.

Referring to Figs. 4 and 5, the bearing 100 block 12 for the gage roll *d* supports a stationary shaft or pin 60 located above and in line with the gage roll and secured in said bearing by the screw 61. The shaft 60 has loosely mounted on it, a gear 62 which meshes with a gear or pinion 63 fastened to the shaft 64 of the gage roll *d* as by the key 65. The stationary shaft 60 has loose on it between the bearing 12 and the gear 62 a lever 66, and beyond the gear 62 a roller 67, 110 and beyond the roller 67 the hub 68 of a lever 69, which parts are retained on said shaft by a nut 70. The roller 67 is adapted to engage the upper surface of the gage 40 and is provided as shown with an elongated hub 115 which is adapted to bear against the hub of the gear 62. The levers 66, 69 support a shaft 71 upon which is loosely mounted a gear 72 which meshes with and is driven by the gear 62. The gear 72 has mounted on 120 its hub a second gear 73, which is adapted to be engaged with the rack bar 41 to produce travel thereof in one direction, which may be termed the forward direction indicated by the arrow 74 in Fig. 3, which direction is the same as that in which the leather is fed out of the machine when the leather is being cut, as represented in Fig. 7. The gear 73 meshes with a gear 75 loose on a shaft 76 supported by levers 77, 78, which are mounted 125

on the intermediate shaft 71. The gear 75 is normally held out of engagement with the rack bar 41 while the latter is being moved in its forward direction, but is adapted to be engaged with said rack bar to cause the latter to be moved backward or in the direction opposite to that indicated by the arrow 74. The gear 75 may be normally held in an elevated or non-operative position, which condition is represented in Fig. 3, by a spring arm or rod 79 which is secured at one end to a side frame 19 of the machine as by the screws 80 (see Fig. 3), and has its free end engaged with or connected to the lever 77, and for this purpose, the spring rod 79 may be provided with a bent finger 81 (see Fig. 4) which is adapted to enter a suitable hole 82 in the lever 77 (see Fig. 9). The gear 73 may be normally held in its lowered or operative position by a helical spring 84 (see Fig. 3), which is interposed between a lug 85 extended from the bearing 12 and an arm 86 on the lever 66, the upward movement of the arm 86 being limited by a stop, shown as a lug or projection 87 on the bearing 12.

Provision is made for automatically disengaging the gear 73 from the rack bar 41 when the latter has completed or substantially completed its forward movement in the direction indicated by the arrow 74, which movement of the rack bar is completed when the leather has been fed out of the machine and the knife has finished its cut. The automatic disengagement of the gear 73 from the rack bar is effected by a cam or projection 90 on the slide plate or bar 50 (see Fig. 3) engaging a projection or boss 91 on the underside of the lever 69, the cam 90 causing the lever 69 to be turned upward on the shaft 60 as a pivot and lifting the gear 73 out of engagement with the rack bar 41. The cam 90 and boss 91 are of such size as to turn the lever 69 a sufficient distance to prevent re-engagement of the gear 73 with the rack bar 41 by the spring 84, when the operator relieves the pressure on the handle 23, which he does when the cut or scarf is finished and the gage roll is moved into its elevated position to permit an uncut piece of leather to be inserted into the machine between the gage roll and the ring roll. When the gear 73 is disengaged from the rack bar 41, by the engagement of the cam 90 with the lever 69, the operator may continue to hold the handle 23 down, if he so desires, in which case the gage roll continues to be driven but does not move the rack bar owing to the disengagement of the gear 73. To reverse the motion of the rack bar, and thereby bring the gage back into its starting position, the operator releases the handle 23 and allows the springs 22 to lift the gage roll carrier upward into its elevated position, which upward movement may be limited by engagement of

The gage roll carrier on its upward movement carries with it the bearing 12, the shaft 60 and the levers 66, 69 mounted thereon, the shaft 71 carried by said levers, and the ends of the levers 77, 78 mounted on the shaft 71. The upward movement of the lever 77 is resisted by the spring arm or rod 79, so that at or about the time, the gage roll carrier has reached the limit of its upward movement, the lever 77 is turned on the finger or projection 81 as a pivot and its free end is lowered so as to engage the gear 75 with the rack bar, which is driven or moved by the gear 75 in a direction opposite to that indicated by the arrow 74. The rack bar is moved backward by the gear 75 until it reaches substantially its starting position, whereupon, the gear 75 is automatically disengaged from the rack bar and the latter stopped in its starting position, which may be effected as herein shown, by a stud or projection 95 on the bar 55 (see Figs. 5 and 9), which engages the inclined end 96 of a lever 97 pivoted at 98 to the frame 42 carrying the rack bar, the said lever engaging a nose or projection 99 on the lever 77. On the forward movement of the rack bar, the stud or projection 95 is carried out of engagement with the lever 97, and the said lever is turned on its pivot by the nose 99 on the lever 77 so as to elevate the inclined or cam-shaped end 96 of the lever 97 into the path of movement of the stud 95, when the lever 77 is turned so as to engage the gear 75 with the rack bar as above described. As a result, the inclined end 96 of the lever 97 is thus brought into position to be engaged by the stud 95 on the backward movement of the rack bar, the said stud forcing the front end of the lever down into the position shown in Fig. 3 and causing the rear end of said lever to elevate the lever 77 and disengage the gear 75 from the rack bar, the lever 77 being held in its elevated position by the spring arm or rod 79. The rack bar and its attached gage are arrested in their backward movement by a stop, herein shown as a lever 100 (see Fig. 3) which is adapted to be engaged by a lug or projection 101 on the gage 40.

The stop lever 100 is adjustably secured to the frame 42 by a bolt 102 having its head fitted to slide in a T-shaped slot 103 in said frame and the plate 44, and the said lever is secured in its adjusted position by the nut 104. The lever 100 is provided with an arm 105 extended up over the frame 42 and carrying an adjusting screw 106, which engages the upper surface of said frame and is employed to turn the said lever on its pivot 102 and raise or lower the front end of the lever 100 with relation to the lug or projection 101 on the gage, to thereby properly position the stop lever with relation to said lug or projection. The stop lever is adjustable on the frame 42 to permit the gage to be adjusted

on the rack bar according to the length of cut desired. As represented in Fig. 3, the gage is set for a substantially short cut of a given angle or bevel, the length of cut being represented in Fig. 3 by the distance from the center of the projection 54 to the center of the bolt 49. If it is desired to make a longer cut, the stop lever 100 is first moved toward the right (viewing Fig. 3), after which the nut 51 is loosened sufficiently to permit the plate 50 to be moved toward the right until the distance between the center of the bolt 49 and the center of the pin or projection 54 equals the length it is desired the cut should be, whereupon the nut 51 is set up to fasten the slide 50 to the rack bar 41. When the gage has been adjusted on its carrier, which, in the present instance, is the rack bar 41, the stop lever is adjusted to engage the lug or projection 101 and secured to the frame 42 in its adjusted position.

The horizontal or back table *m* has secured to its upper surface as by one or more bolts 110, (see Fig. 6) a back stop herein shown as 25 a bar 112, which is adjustably secured to said table and positioned with relation to the gage roll according to the length of the scarf or cut it is desired to make.

The operation of the machine herein shown 30 may be briefly described as follows:—Assume the machine in the position represented by full lines in Fig. 2, namely, with the gage roll in its elevated position and the handle 23 in its full line position, and the gage 40 at 35 rest in the position represented in Fig. 3. The operator places a piece of leather, such, for instance, as a piece of leather belting, in the machine, that is, between the elevated gage roll and the ring roll, until the end of the 40 piece of leather strikes the back stop or work gage 112. The lever or handle 23 is then moved downward as indicated by dotted lines Fig. 2, which movement brings the gage roll into contact with the upper surface of 45 the leather and grips the same between it and the ring roll. If the leather is of substantially the same thickness as the distance between the gage roll and ring roll, when the roller 67 is brought into engagement with the 50 gage 40, as represented in Fig. 3, which thickness may be regarded as the minimum thickness, the knife *f* commences to cut on an incline extending from the under surface of the leather to the upper surface at the end or 55 edge of the same. If however, the leather is somewhat thicker than the minimum, the knife makes a deeper initial cut, which extends into the leather until the thickness of the uncut leather is substantially the minimum, after which the knife cuts on the same 60 bevel or angle it does when the leather is of minimum thickness. When the gage roll is brought down into engagement with the leather, the latter is fed out of the machine by 65 the gage roll and ring roll, the same as is done

in the ordinary construction of belt knife splitting machines. As the leather is fed out of the machine against the cutting edge of the knife, which movement of the leather is in the direction indicated by arrow 74, Figs. 70 3, 6 and 7, the inclined gage 40 and its carrier or rack bar are moved in the same direction, and the movement of the gage roll toward the ring roll or support for the leather, while the leather is being cut, is automatically controlled by the gage 40, with the result that the angle or bevel of the cut is maintained clear to the edge of the leather, and the latter is firmly gripped between and held by the gage roll and ring roll even to the edge of the 80 leather, while under the action of the knife, with the result, that the scarf or cut may be carried to a very thin edge without danger of tearing the leather. The movement of the gage 40 co-incident with the feed of the 85 leather out of the machine, is effected as above described, by the gear 73 meshing with the rack bar. When the material has been cut or scarfed and fed out of the machine, the cam 90 disengages the gear 73 from the rack 90 bar and the operator relieves the pressure on the handle 23, which allows the springs 22 to move the head of the machine carrying the gage roll, upward into its starting position. At or about the time the movable head of the 95 machine has reached the limit of its upward movement, the reversing gear 75 is engaged with the rack bar, and the latter and its attached inclined gage 40 is moved back into its starting position, namely, with the lug or 100 projection 101 in engagement with the back stop 100, the gear 75 being disengaged from the rack bar by the lever 97 acted upon by the stud 95, at or about the time the rack bar reaches its starting position. This operation 105 is repeated as long as it is desired to cut scarfs of the same length and angle or bevel. When, however it is desired, to cut a longer scarf, the gage 40 is adjusted on its carrier as 110 above described.

It will be observed that the thick and thin pieces of material are provided with a cut of substantially the same length and angle or incline, thereby avoiding waste of material. It is also to be observed that the initial cut 115 is a little deeper in the thicker material, which may require a very slight amount of hand labor to finish the scarf or cut on the thicker pieces. In practice, the gage 40 is set to correspond to the minimum thickness of material. It will be understood, that in practice, the pieces of leather or material to be scarfed, are sorted so as to be as nearly uniform in thickness as is practicable.

I have herein shown one construction embodying this invention, but I do not desire to limit my invention to the particular construction shown. Furthermore, the invention is shown as applied to a belt knife splitting machine of ordinary construction, which 130

is capable of being used as a splitting machine, by merely loosening the gage 40 and permitting it to hang down on its pivot, or by removing said gage from the machine, and 5 while I may prefer to apply the invention to a splitting machine, I do not desire to limit my invention in this respect, as it may be embodied in a machine which is used only for scarfing purposes. The movable bearing 10 32 for the pressure rods 29 is centered between the side plates or pieces 13, 14 of the movable head of the machine by the screw-threaded plugs 33 which are adjustable in threaded holes in said side pieces.

15. Claim.

1. In a machine of the class described, in combination, a bed roll, a ring roll co-operating therewith, a gage roll movable toward and from said ring roll, an endless band or 20 belt knife adapted to cut the material as it is fed from between the said gage roll and said ring roll, means to move said knife, an inclined gage arm or bar, a rack bar to which said gage arm is secured, a frame in which 25 said rack bar is supported, a driving gear to move said rack bar in one direction, a shaft upon which said gear is mounted, levers to support said shaft, gearing to connect said driving gear with the gage roll, a second gear 30 to reverse the motion of said rack bar, a shaft on which said reversing gear is mounted, levers pivoted upon the shaft of the said driving gear and in which the shaft of the reversing gear is supported, a cam movable 35 with the rack bar to disengage the driving gear from said rack bar, a lever to disengage the reversing gear from said rack bar, a device movable with said rack bar to actuate said disengaging lever, a spring rod or arm 40 to hold the reversing gear in its disengaged position, and a stop to limit the reverse movement of said rack bar, substantially as described.

2. In a machine of the class described, in combination, a rotatable support for the material to be cut, a rotatable gage roll co-operating with said support and movable toward and from the same, a movable knife to cut the material fed from between said support 45 and gage roll, an inclined gage bar or arm to control the movement of said gage roll toward said support, a carrier for said gage bar or arm, means to drive said carrier in one direction in a plane substantially at right 50 angles to the plane in which said gage roll is moved, means to move said carrier in a reverse direction, means to disengage said driving mechanism from said carrier, means to disengage said reversing mechanism from 55 said carrier, and a stop to arrest the carrier in its movement in the reverse direction, substantially as described.

3. In a machine of the class described, in combination, a bodily movable gage roll, a

support for the material located below said 65 gage roll, and a knife to cut the material, an inclined gage controlling the bodily movement of the gage roll toward said support according to the cut made in said material by said knife, and mechanism to move said 70 gage in a path substantially at right angles to the path in which the gage roll is moved, substantially as described.

4. In a machine of the class described, in combination, a rotatable gage roll to engage 75 the material, means to effect bodily movement of said gage roll, a knife to cut said material, a gage to control the bodily movement of the gage roll toward said knife, and mechanism driven from said gage roll to 80 effect movement of said gage in a path at an angle to the path in which the gage roll is moved bodily, substantially as described.

5. In a machine of the class described, in combination, a rotatable bed roll, a ring roll 85 co-operating therewith, a rotatable gage roll located above and movable toward and from said ring roll, means to move said gage roll toward said ring roll, a movable endless knife adapted to cut the material as it is fed from 90 between said gage roll and ring roll, means to move said knife, a gage movable in a direction substantially at right angles to that in which the gage roll is moved to regulate the downward movement of said gage roll according to the cut in the material made by the said knife, power operated mechanism to move said gage in opposite directions, and means to automatically reverse the movement of said gage when it has reached substantially 95 the end of its movement in opposite directions, substantially as described.

6. In a machine of the class described, in combination, a bed roll, a ring roll co-operating therewith, a gage roll movable toward 105 and from said ring roll, an endless knife arranged substantially on a level with said ring roll and engaging the under side of the material interposed between said gage roll and said ring roll, means to move said knife, an 110 inclined gage to control the movement of said gage roll toward said ring roll, a carrier for said gage, means to drive said carrier in one direction in a plane substantially at right angles to the plane in which said gage roll is 115 moved, means to move said carrier in a reverse direction, means to disengage said driving mechanism from said carrier, and means to disengage said reversing mechanism from said carrier, substantially as described.

7. In a machine of the class described, in combination, a knife to cut the material, devices between which the material is gripped while being cut by said knife, means to effect 120 bodily movement of one of said devices toward the other, and a gage interposed in the path of movement of said bodily movable de-

vice to limit its movement toward the other of said devices according to the cut made by the knife, substantially as described.

8. In a machine of the class described, in combination, a reciprocating gage, a rack bar to which said gage is attached, and mechanism to reciprocate said rack bar, said mechanism comprising a gear to move said rack bar in one direction, a second gear to move said rack bar in the opposite direction, means to rotate said gears, and means to automatically effect engagement of said gears alternately with said rack bar substantially at the end of the movement of said gage in opposite directions, substantially as described.

9. In a machine of the class described, a rack bar provided with a longitudinally extended slot or guideway, a bolt movable in said guideway, an inclined gage bar or arm mounted on said bolt, means to clamp said inclined gage arm to said rack bar to move therewith, and means to move said rack bar, substantially as described.

10. In a machine of the class described, in combination, an inclined gage, a movable carrier to which said gage is secured, mechanism to move said carrier in a substantially horizontal path, means to automatically disengage said mechanism from said carrier when the latter reaches substantially the end of its movement in one direction, mechanism to move said carrier in a reverse direction, and means to automatically disengage said reversing mechanism from said carrier when the latter reaches substantially the end of its movement in the reverse direction, substantially as described.

11. In a machine of the class described, in combination, a gage bodily movable in a substantially horizontal path, mechanism for moving said gage in said path, and means attached to said gage for rendering said mechanism inoperative when the gage has reached substantially the end of its movement in one direction, substantially as described.

12. In a machine of the class described, in combination, a gage bodily movable in a substantially horizontal path, mechanism for moving said gage in said path, and means movable with said gage for rendering said mechanism inoperative when the gage has reached substantially the end of its movement in one direction, mechanism for moving said gage in a reverse direction, and means movable with said gage for rendering said re-

versing mechanism inoperative when the gage has reached substantially the end of its movement in the reverse direction, substantially as described.

13. In a machine of the class described, in combination, a gage roll movable in a substantially vertical path means to move said gage roll, a gage movable in a substantially horizontal path and controlling the movement of the gage roll in one direction in said vertical path, and mechanism for moving said gage in said horizontal path, substantially as described.

14. In a machine of the class described, in combination, a gage roll movable in a substantially vertical path means to move said gage roll, a gage movable in a substantially horizontal path and opposing the movement of the gage roll in one direction in said vertical path, and mechanism actuated by said gage roll for moving said gage in said horizontal path, substantially as described.

15. In a machine of the class described, in combination a gage roll movable in a substantially vertical path, means to move said gage roll in said vertical path, a gage movable in a substantially horizontal path and opposing the movement of the gage roll in one direction in said vertical path, mechanism for moving said gage in opposite directions in said horizontal path, and means to render said mechanism inoperative to move said gage when the latter reaches substantially the end of its movement in opposite directions, substantially as described.

16. In a machine of the class described, in combination, a bed roll, a ring roll co-operating therewith, a gage roll movable toward and from said ring roll, a movable endless knife adapted to cut the material as it is fed from between said gage roll means to move said knife and ring roll, and a gage movable in a direction substantially at right angles to that in which the gage roll is moved to regulate the movement of the said gage roll toward said ring roll according to the cut made by the knife in said material, substantially as described.

In testimony whereof, I have signed my name to this specification in the presence of two subscribing witnesses.

CHARLES F. STACKPOLE.

Witnesses:

JAS. H. CHURCHILL,
J. MURPHY.
